UNITED STATES PATENT OFFICE.

BRUNO NITZ, OF BERLIN-REINICKENDORF, GERMANY, ASSIGNOR TO THE FIRM OF
WILH. KÖRTING, OF BARMEN, GERMANY.

PLAITING-MACHINE.

1,144,080.

Specification of Letters Patent. Patented June 22, 1915.

Application filed December 8, 1914. Serial No. 876,169.

To all whom it may concern:

Be it known that I, BRUNO Nitz, engineer, a citizen of the German Empire, and residing at Berlin-Reinickendorf, Germany, have 5 invented certain new and useful Improvements in Plaiting Machines, of which the following is a specification.

Plaiting machines are known in which there are two concentric rows of bobbins and 10 in which the inner row of bobbins is moved by means of intermediate gear wheels that are driven by a ring of teeth which form a part of a rotor, the rotor serving also as a support for the outer row of bobbins. Machines of this kind are also known having a 15 fixed divided guide for the inner row of bobbins which latter is moved around a plane circle, while the outer bobbins are moved along a curved path that passes 20 above and under the inner bobbins.

The present invention consists chiefly in a new arrangement of the rotating elements for producing a turning movement of the inner row of bobbins opposite to the turning 25 movement of the outer row, the object of the new arrangement being to provide a clear path along or through which the plaiting strand or strands from the outer row of bobbins may be passed. By this means 30 disadvantages are to be prevented which are present in efficient machines of the same type.

A drawback removed by the invention in machines in which the outer bobbins are 35 moved along a cycloid-shaped path for example is, that only plaits in which one outer strand is crossed by three inner strands can be made. The twisting of the outer threads that takes place in the cycloid path machines 40 is also avoided. It is also rendered unnecessary to pass the strands or threads between rollers, strong threads only being capable of resisting the squeezing and hard usage involved in this process.

45 Another feature of the invention consists in intermediate differential rollers or gear wheels being driven by a ring of teeth fixed to a slotted rotor and that the differential wheels drive the carriers of the one row of 50 bobbins in a direction opposite to that in which the rotor is moved. Since this involves only one ring of teeth the construction of the machine is cheapened.

The slots in the rotor are provided to enable the passing through of the outer thread.

An additional advantage of the arrangement just described is that it avoids the outer thread crossing the driving gear at the lowest point of the curved path that this thread described, which renders the slot 60 and thread more liable to be soiled. In order to be able to substitute the narrow-slots in the rotor by broad spaces and to thus entirely obviate the soiling of the plaiting strands, intermediate wheels are arranged 65 between the existing driving wheels and serve to connect these wheels together. This feature of the invention enables a larger number of teeth to be omitted in the ring of teeth attached to the rotor than hitherto and 70 this renders it possible to provide spaces which are large enough to allow of the thickest plaiting strands, or of a guide, being used for the outer plaiting strand, which 75 guide may be made to act as a protector.

Another feature of the invention consists of an arrangement by which the bobbins of the inner row are placed on the side of the bobbin carrier or of the bobbin carrier guide that is farthest from the point at which the threads are plaited together. By this arrangement it is possible to decrease the diameter of the guide body and hence the diameter of the path traversed by the inner bobbin carrier as well as that of the driving gear to the lowest possible limit. An 80 economical advantage resulting from this is that the plaiting machines may execute a much larger number of revolutions per minute without increasing the peripheral speed 85 of the inner bobbin carrier and that of the toothed wheels.

The invention is illustrated in the drawings, similar or equivalent parts in the various figures having similar reference characters.

Figure 1 is an elevation and a partial vertical section of the machine. Fig. 2 represents in a larger scale the manner of operation of the inner bobbin carrier. Fig. 3 100 is a section on the line A—B of Fig. 2. Fig. 4 illustrates an elevation and a partial section of a modified form of operating mechanism for the inner bobbin carrier. Fig. 5 is an enlarged elevation of a fragment of the machine of Fig. 4, the driving gear of which is propelled by a single ring of teeth. Fig. 6 shows a section on the line A—B of Fig. 5. Fig. 7 represents a cross-section through the propelling gear of Fig. 110

5, showing a modification in which two rings of teeth are employed. Fig. 8 is a diagram of a feature of the invention according to which the plaiting machine of Figs. 1 to 3 and 7 is provided with an inner row of bobbins which is arranged at the outer side of the guide way of these bobbins.

Fixed to the baseplate 1 is an upright 2 upon which is mounted a support 3 the periphery of which is formed in the shape of a guide for the inner row of bobbins. The upper guide way support 4 whose central axis coincides with that of the lower guide frame 3 may be fixed to the two standards 5 and 6. Revolvably mounted on the upright 2 is a rotor 7 that is rotated through bevel wheels 8 and 9 by the belt pulleys 10. The rotor 7 is provided with a ring of teeth 11 and a second ring of teeth 13 of equal size 20 is fixed above the ring 11 by spacing pieces 12. Groups of intermediate gear wheels 14 are mounted at different points of the circumference in the lower and upper guide way support and are in permanent engagement with the two rings of teeth. The inner bobbin carriers 15, which slide along a guide-way at the periphery of the guide frame 3, are provided with teeth at their top and lower edges. When the rings of 30 teeth 11, 13 and the groups of intermediate toothed wheels 14 rotate the bobbin carriers are moved along the guide way by the alternative engagement of their lower and upper rows of teeth with the teeth of the intermediate wheels. The guide way along which the bobbin carrier travels alternates between the lower and upper guide way supports 3 and 4 respectively. This arrangement permits of the outer plaiting strands 40 which are taken from an outer circular row of bobbins, for instance as shown in Figs. 1, 3, being passed along a wave-shaped path over and beneath the inner bobbins without striking against obstacles. When the rings of teeth 11 and 13 that are fixed to the rotor 7 are rotated the engagement of intermediate wheels 14 with the lower and upper rows of teeth of the bobbin carriers 15 causes these to move in a direction opposite 50 to that of the rings of teeth as indicated by the arrows in Fig. 2. From this figure it will also be seen that at the moment when a bobbin carrier 15 leaves a lower section of guide way it slides onto an upper guide-way section.

According to the feature of the invention shown in Figs. 4 to 7 the rotor 7 has a ring of teeth 11 or rings of teeth 11 and 13 (Fig. 7) that are directed inwardly. Permanently engaged with these rings of teeth are the intermediate toothed wheels 14 which are mounted on the same shafts as smaller toothed wheels 14^a. In order that the speed of revolution of the ring of teeth 65 and of the bobbin carriers may be the same

the ratio between the diameters of the intermediate wheels 14 and 14^a is the same as the ratio between the ring of teeth 11 and the circle described by the rows of teeth of the inner bobbin carrier 15. The axes of 70 the intermediate wheels 14 and 14^a run parallel to the axis of the machine and they are mounted in groups alternatively on the bottom and upper guide way support at different points of the circumference of the machine. The inner bobbin carriers are driven alternatively by lower and upper groups of intermediate wheels and shift from lower guide-way sections to upper guide-way sections. When the rotor 7 with its ring of 75 teeth 11 or rings of teeth 11 and 13 (Fig. 7) revolves the inner bobbin carrier 15 is moved by the differential intermediate wheels 14 and 14^a that engage the ring of teeth and with the teeth of bobbin carrier. 80 The bobbin carrier rotates at the same speed as the rotor but in the opposite direction. If two rings of teeth 11 and 13 (Fig. 7) are used the outer plaiting strand oscillates along a curved path between the two rings, 85 but in a machine with only one ring of teeth, as illustrated in Fig. 6, the ring is located in the plane of the inner bobbin carriers or beneath this plane. In the latter case the rotor must be provided with slots or notches 90 (see 17 in Fig. 5) into which the outer plaiting strands may enter during their passage beneath the inner bobbins.

The machine represented in Fig. 8 differs from that shown in Figs. 1 to 3 only in that 95 the two rings of teeth 11 and 13 are held together by spacing pieces that are bent far outward in order that the inner row of bobbins, which in this case is fixed to the outer surface of the bobbin carrier 15, may move 100 without hindrance past the rotor 7 that rotates in the opposite direction. The inner plaiting strand may be passed through a hole 16 of the inner bobbin carrier to the center where the plaiting operation takes 105 place.

I claim:—

1. Plaiting machine comprising two concentric rows of strand bearing bobbins, a rotor for rotating the outer row of bobbins, 115 means for moving the strands of the outer bobbins to and fro in the circular path of these bobbins, bobbin carriers supporting bobbins of the inner row of bobbins, a ring provided with teeth on said rotor, racks on 120 the said bobbin carriers and gearing engaged by the said ring of teeth and alternatively engaging first the one rack of a bobbin carrier and then another rack of a said carrier and thereby rotating the same in the 125 opposite direction to the rotor.

2. A plaiting machine comprising two concentric rows of strand bearing bobbins, a rotor for rotating the outer row of bobbins, means for moving the strands of the 130

- outer bobbins to and fro in the circular path of these bobbins, bobbin carriers supporting bobbins of the inner row of bobbins, upper guide-ways and lower guide-ways for 5 the said carriers, a ring provided with teeth on said rotor, racks on the said bobbin carriers and gearing engaged by the said ring of teeth and alternately engaging first the one rack of a bobbin carrier and then another rack of a said 55 carrier and thereby rotating the same in the opposite direction to the rotor, said inner bobbins being mounted on the sides of the said carriers that are turned away from the carriers' center of rotation. 60
6. A plaiting machine comprising two concentric rows of strand bearing bobbins, a rotor for rotating the outer row of bobbins, means for moving the strands of the outer bobbins to and fro in the circular path of these bobbins, bobbin carriers supporting bobbins of the inner row, upper guide-ways and lower guide-ways for the said carriers, a ring provided with teeth on said rotor, racks on the said bobbin carriers and gearing engaged by the said ring of teeth and alternately engaging first the one rack of a bobbin carrier and then another rack of a said carrier so as to rotate it in the opposite direction to the said rotor, the said inner 65 bobbins being mounted on the sides of the said carriers that are turned away from the carriers' center of rotation. 70
7. A plaiting machine comprising two rows of strand bearing bobbins, a rotor for moving the one row of bobbins in a circle, two rings of teeth fixed to the rotor, driving wheels placed at different points of the circumference of the machine and engaging with the said rings, bobbin carriers for the inner row of bobbins, and racks at different 75 parts of each bobbin carrier which engage alternately with different ones of the said driving wheels and by which the bobbin carriers are moved in a circle in the opposite direction to the said toothed rings. 80
8. A plaiting machine comprising rows of strand bearing bobbins, means for moving the one bobbin row in a circle, means for moving a second bobbin row in a circle inside the first circle and in an opposite direction to the first row, means for moving the strands of the outer bobbin row to and fro in the circular path of these bobbins, means for moving the strands of the inner bobbins in a plane circular path and bobbin carriers for the inner row of bobbins, the said moving means for the second bobbin row comprising driving means for the bobbin carriers which engage with the carriers at different surfaces of the same alternately, the said inner bobbins being mounted on the sides of the said carriers which are directed outward from the center of their circular paths. 85
9. A plaiting machine comprising two concentric rows of strand bearing bobbins, a rotor for rotating the outer row of bobbins, means for moving the strands of the outer bobbins to and fro in the circular path of these bobbins, bobbin carriers supporting bobbins of the inner row, a ring 90 porting bobbins of the inner row, a ring
- provided with teeth on said rotor, racks on the said bobbin carriers and gearing engaged by the said ring of teeth and alternately engaging first the one rack of a bobbin carrier and then another rack of a said carrier and thereby rotating the same in the opposite direction to the rotor, said inner bobbins being mounted on the sides of the said carriers that are turned away from the carriers' center of rotation. 95

In testimony whereof I affix my signature in presence of two witnesses.
